UNITED STATES PATENT OFFICE.

SAMUEL LEE GARNER, OF TULSA, OKLAHOMA.

Slicing-Machine.

940,867.

Specification of Letters Patent. Patented Nov. 23, 1909.

Application filed September 14, 1908. Serial No. 453,000.

To all whom it may concern:

Be it known that I, SAMUEL LEE GARNER, a citizen of the United States, residing at Tulsa, in the county of Tulsa and State of Oklahoma, have invented a new and useful Slicing-Machine, of which the following is a specification.

This invention relates to machines for slicing bread, vegetables, etc., and its object 10 is to provide a simple and compact machine of this character having a number of knives designed to be simultaneously shifted into engagement with the object to be sliced, simple and efficient means being employed 15 whereby these knives can be readily manipulated.

Another object is to provide a series of knives which can be quickly adjusted toward or from each other to regulate the thicknesses of the slices to be cut.

Another object of the invention is to provide means for automatically engaging the object to be sliced, said means being shiftable out of engagement with the object when 25 the knives are withdrawn therefrom or elevated.

With these and other objects in view the invention consists of certain novel details of construction and combinations of parts 30 hereinafter more fully described and pointed out in the claims.

In the accompanying drawings the preferred form of the invention has been shown.

In said drawings:—Figure 1 is a perspective view of the machine, the sides being shown partly elevated. Fig. 2 is a longitudinal section through the machine, the knives being shown in their normal position.

Referring to the figures by characters of 40 reference 1 designates a table of any suitable proportions and mounted on legs 2. Arranged upon this table, preferably at one end, is a frame consisting of side walls 3 and an end wall 4, there being suitable braces 5 connecting the walls and table so as to hold 45 said walls securely in proper position. Arranged upon the inner surface of each side wall 3 are parallel guides 6 forming a channel 7 therebetween within which is mounted 50 a slide 8. The two slides constitute bearings for the end portions of a cross-rod 9 to which is secured an end strip 10, having a longitudinal slot 11 therein for the purpose 55 hereinafter set forth. Springs 12 connect the end portions of the rod 9 with the cor-

responding portions of another rod 13 which is mounted within and between the side walls 3 and close to the end wall 4. The rod 9 is therefore held normally adjacent the rod 13 with the slides 8 positioned in the upper ends of the guide-ways or channels 7.

Extending through the slot 11 is a series of stems 14, each stem having a screw-threaded end portion on which are mounted nuts 15 arranged at opposite sides of the end plate 11 and designed to clamp thereon so as to rigidly hold the said stems 14 in any positions to which they may be adjusted relative to the end strip 10. Each stem 14 extends beyond the butt or heel end 16 of a blade 17. Each blade 17 is substantially triangular in outline and extending from the small end thereof is a stem 18 having a screw-threaded portion extending through a slot 19 formed longitudinally within an end plate 20. Each of these threaded portions is provided with nuts 21 or other suitable clamping devices disposed at opposite sides of the end plate 20 and designed to clamp thereon so as to hold the stems 18 properly spaced apart and in the positions to which they may be adjusted. The blades 17 are so proportioned that when they are swung downward to the limit of their movement the lower or cutting edges thereof will rest 85 upon the table 1 throughout their lengths.

Pivotedly mounted on the rod 13 is an actuating lever 22 to which is pivotally connected a stem 23 of a yoke 24. The terminals of this yoke are pivotally connected 90 to two of the blades 17 and extending downwardly from the stem 23 adjacent its point of connection with the lever 22 is an arm 25 constituting a stop designed to move into contact with one or more of the blades and 95 thus positively insure the downward movement of said blades through objects placed thereunder. An eye 26 is formed on the lever 22 and is designed to engage a hook 27 arranged on a frame 28 upstanding from the 100 walls 3. The lever 22 when thus placed in engagement with hook 27 will be supported in elevated position and the knives 17 will also be upheld so that any object to be sliced can be readily placed on the table 1 105 and in the path of the knives or blades 17.

Upstanding from the table 1 is a series of spaced fingers 29 which are perfectly rigid and designed, when the blades 17 are resting on the table, to extend between said blades. 110

A series of slots 30 are formed within the table between the fingers 29 and the walls 3 and 4 and extending downward from the table adjacent the ends of the series of slots 30 are hangers 31 constituting bearings for a rock bar 32. Extending upwardly from this rock bar is a series of fingers 33 projecting through the slots 30 and designed to co-operate with the fingers 29 in the manner hereinafter set forth.

10 A short arm or projection 24 extends downwardly from the rock bar 32 and is connected by means of a spring 35 with a hanger or hangers 36 depending from and rigidly connected to the table 1. These 15 springs constitute means for holding the fingers 33 normally inclined upwardly and away from the fingers 29. A grooved wheel or pulley 39 is mounted upon one end portion of the table 1 and guided on this pulley 20 is a chain 40 or other flexible device one end of which is attached to the lever 22 at a point removed from the pivot thereof as indicated at 41 while the other end of the 25 chain is secured to a spring 42 attached to an armor projection 34 extending downwardly from the rock bar 32. These parts 30 are so positioned that when the lever 22 is swung downward into its lowermost position the chain 40 will pull on the spring 42 with sufficient force to swing the rock bar 32 and cause the fingers 33 to move in the direction of the fingers 29. When however the 35 lever 22 is raised the stress of the spring 42 will be removed and the spring 35 will be free to return the fingers 33 and the rock bar to their normal positions.

When it is desired to use this machine the lever 22 is raised and placed in engagement with the supporting hook 27. As before stated this operation will result in the fingers 33 being moved away from the fingers 29 by the spring 35. Bread, vegetables, or other articles to be sliced are then placed 45 on the table 1 between the fingers 29 and 33 and the lever 22 is released from its supporting hook 27 and swung downwardly. Spring 42 and chain 40 will thus pull on the arm 34 and cause the fingers 33 to swing against and bind upon the article so as to hold it firmly while the slicing operation is taking place. As the lever 22 swings downward it transmits motion through the link 23 to the series of blades 17 causing said 55 blades not only to swing downwardly with the rod 9 as a pivot but also to move longitudinally, this being permissible in view of the fact that the members 8 are mounted to slide between the guides. A shearing action 60 is thus produced which insures a smooth clean cut of the object held beneath the blades. The arm 25 is designed to swing downward against one or more of the blades 17 so as to positively force the blades into 65 the object thereunder. When the lever 22

is swung upwardly so as to return the blades 17 to their initial positions, this return being facilitated and completed by the springs 12, the chain 40 is let out so as to reduce the stress of the spring 42, and thus permit the 70 spring 35 to return the fingers 33 to their initial or normal positions. The sliced material can thus be readily removed from between the fingers 29 and 33. It is of course to be understood that the fingers 29 and 33 75 are so located as to project between the blades 17. By loosening the stems 14 and 18 within the slotted end plates 10 and 20 the blades can be shifted toward or from each other so as to regulate the thicknesses of 80 the slices produced.

What is claimed is:—

1. The combination with a supporting structure; of a member slidably mounted thereon, a series of spaced, parallel blades 85 pivotally connected to said member, an actuating lever, means for transmitting motion from the said lever to the blades, a stop device movable with the lever for engagement with one of the blades, and yielding means for holding the sliding member normally in predetermined position.

2. The combination with a supporting structure; of a slidably supported end plate having a longitudinal slot therein, a series 95 of parallel, spaced blades, stems extending therefrom and adjustably mounted within the slotted end plate, means for adjustably connecting the blades at a point removed from said end plate, and means for actuating the blades simultaneously.

3. The combination with a supporting structure; of fixed gripping fingers thereon, oscillating gripping fingers co-operating therewith, yielding means for holding said 105 oscillating fingers normally in a predetermined position, adjustably connected cutting blades movably supported above and disposed to move between the fingers, and elastic means operated by the movement of 110 the blades in one direction for shifting the oscillating fingers out of normal position.

4. The combination with a supporting structure having a series of slots therein, and fixed clamping members disposed adjacent 115 the slots; of a rock-bar, clamping fingers extending therefrom and through the slots, parallel cutting blades movably mounted upon the supporting structure, means for actuating the same, said blades being movable 120 between the fingers and the fixed clamping members, and yielding means operated by said actuating means for shifting the fingers into clamping position.

5. In a device of the class described a 125 supporting structure having a series of parallel slots therein, fixed spaced clamping members upstanding from said structure and adjacent the slots, a series of clamping fingers movably mounted within the slots 130

and shiftable together, means for yieldingly holding said fingers normally in a predetermined position, a series of parallel cutting blades slidably and pivotally mounted upon the supporting structure and movable between the clamping fingers and the fixed clamping members, means for actuating said blades, and yielding means operated by said actuating means for shifting the fingers into

clamping position during the cutting action 10 of the blades.

In testimony that I claim the foregoing as my own, I have hereto affixed my signature in the presence of two witnesses.

SAMUEL LEE GARNER.
